UNITED STATES PATENT OFFICE.

BENJAMIN MOTT WIGGINS, OF PHILADELPHIA, PENNSYLVANIA.

DESIGN FOR A BLOTTER FOR CHECK OR SIMILAR BOOKS.

SPECIFICATION forming part of Design No. 28,911, dated June 21, 1898.

Application filed March 7, 1898. Serial No. 673,013. Term of patent 14 years.

To all whom it may concern:

Be it known that I, BENJAMIN MOTT WIGGINS, a citizen of the United States, residing at the city of Philadelphia, in the county of Philadelphia and State of Pennsylvania, have invented and produced a new and original Design for a Blotter for Check or Similar Books, of which the following is a specification, reference being had to the accompanying drawings, forming part hereof, in which—

Figure 1 is a front view of a blotter with its flap of my design. Fig. 2 is a rear view of the same; and Fig. 3 is a cross-sectional view on the line $x-x$ of Fig. 1, these views being deemed essential to a proper illustration of my design.

The leading feature of my design consists of the blotter of oblong shape, on the front face of which are provided ornamental lines forming an oblong panel, the lines crossing at the ends to form a cross-like ornament at or near the corners of the blotter in conjunction with the flap, which, viewed in front elevation, is substantially trapezoidal in shape with the base overlapping one edge of the blotter, and which when viewed in cross-section is bellied or corrugated at or near the edge of the blotter.

In the drawings, a represents the face of

the blotter A , which is oblong in shape and has the ornamental lines a' , forming a centrally-arranged panel a'' , the ends of these lines a' crossing each other to form the cross-like ornaments a'' at or near each of the four corners of the blotter. The rear face a^2 of the blotter is plain. The flap b , when viewed in front elevation, is substantially trapezoidal in shape, with its base b^3 overlapping the adjacent edge of the blotter and having its pyramidal portion b gummed, as at b' . When viewed in cross-section, the flap B is bellied or corrugated, as at b^2 , at or near the edge of the blotter, which is overlapped by the base of the flap.

Having thus described my invention, what I claim as new, and desire to secure by Letters Patent, is—

The design for a blotter for check and similar books, substantially as shown and described.

In testimony whereof I have hereunto set my signature in the presence of two subscribing witnesses.

BENJAMIN MOTT WIGGINS.
